UNITED STATES PATENT OFFICE.

THADDEUS L. POWELL, OF ASHLAND, OREGON.

PENCIL-HOLDER.

1,246,318.

Specification of Letters Patent. Patented Nov. 13, 1917.

Application filed July 19, 1916. Serial No. 110,131.

To all whom it may concern:

Be it known that I, THADDEUS L. POWELL, a citizen of the United States, residing at 5 Ashland, in the county of Jackson and State of Oregon, have invented certain new and useful Improvements in Pencil-Holders, of which the following is a specification.

This invention relates to pencil holders, and has for its object to provide an article 10 of this class which is designed to be carried in the pocket of a garment and be secured to the top thereof and present on the inside of the pocket immediately below the top, one or more resilient clamps into which a pencil 15 may be thrust and which will hold said pencil securely and prevent the same escaping from the pocket when a person carrying the same stoops, or upon removing the garment carelessly throws it upon a piece of 20 furniture, whereby the pocket may be caused to assume such a position that without the device the pencil would escape and fall.

Another object of the invention is to provide a pencil carrier which shall be simple, 25 light, readily secured within the pocket and which can be made very cheaply, and which is of such nature that when placed within the pocket it will not cause the same to bulge and spoil the appearance of a well fitting 30 garment.

A further object of the invention is to provide in connection with the pencil carrier means for protecting the point of the pencil so that however active a person may be or 35 great the pressure placed upon the pocket the pencil point will be thoroughly protected from breaking.

With these as the principal objects in view, the invention consists of the novel construction and arrangement of parts hereinafter 40 described and pointed out in the claims, and illustrated in the accompanying drawings in which:

Figure 1 is a view of a portion of a garment showing the opening for the pocket and the pencil carrier placed therein.

Fig. 2 is a perspective view of the pencil carrier removed from the pocket.

Fig. 3 is a vertical sectional view on the 50 line 3—3 of Fig. 2, and

Fig. 4 is a perspective view of a modified form of the carrier.

In the drawings A indicates a garment such as a vest or coat having a pocket therein 55 opening on the outer side of the garment at B. Within the pocket and secured to the

edge of the opening B is placed the pencil carrier 10 which in a preferred form comprises a rectangular plate 11 made of thin resilient sheet metal the vertical edges of 60 which intermediate the lower and upper ends of the plate 11 are rolled inwardly to form cylinders 12 in which pencils may be carried one in each cylinder. The upper edge of the plate 11 is bent outwardly upon said plate to 65 form a clamping finger 13 which may be of circular formation as shown, or have any other desired configuration. The finger 13 when the pencil holder is placed within the pocket B lies against the outer side of the 70 pocket as shown in Fig. 1 bearing against the same and forming a clamping means for retaining the pencil carrier within the pocket. The fold 14 at the bend of the finger 13 is made somewhat cylindrical as 75 shown to provide the finger 13 with sufficient resiliency to clamp against the pocket.

Between the top of each cylinder 12 and the upper edge of the plate 11 is a continuation of the cylinders and each continuation 80 15 is formed from a lateral projection 16 of the plate 11 made sufficiently long to be bent backward upon themselves as at 17 and then outwardly to form the extension 15, the ends 18 projecting a short distance inwardly from 85 said extensions. These extensions are preferably of slightly less diameter than the cylinders 12 so as to press upon the pencils when inserted therein and downwardly into the cylinder and thus provide sufficient 90 resiliency to prevent the pencils falling therefrom though the pencil carrier be entirely inverted.

The lower end 19 of the plate 11 below the cylinders 12 is folded into a triangular form 95 as shown one side of said triangle being horizontal and bearing against the lower ends of the cylinders 12. Through this horizontal side 20 are made two openings 21 that lie immediately below the cylinders 12 100 and through which the pointed ends of the pencils pass. These pointed ends lie within and are protected by the triangular lower portion 22 of the pencil carrier.

A pencil carrier such as described is simple and can be made very cheaply as the entire device is formed of a single plate of sheet metal cut to proper shape and the parts folded to form the cylinders 12, cylinder extensions 15 and point protectors 22. The 110 folds may be readily made without the use of expensive machinery and turned out with

great rapidity. The finger 13 is the only portion exposed to view and this may be ornamented and made as attractive as the public desires or if desired, it can be skeletonized by cutting out portions thereof and the part that remains exposed enameled in various colors and tints to match the clothing with which it may be worn.

As a modification of the pencil carrier the 10 plate 11 instead of projecting downwardly into the pocket and having the cylinders 12 thereon, may be cut short and rounded on the bottom as at 23, Fig. 4. This plate 23 fits within the pocket to form with the finger 15 13 a clamping device for holding the carrier within the pocket. The pencils in this form of the device are held by extensions 15 like those in the preferred form of the device and which being resilient and presenting an opening slightly less than the diameter of the pencil will securely clamp the pencil when inserted therein.

I claim—

1. A pencil carrier comprising a sheet 25 metal plate having a spring finger at one end to support the carrier within the pocket of a garment, vertical tubular pencil supports formed on said plate at the edges thereof intermediate the ends, a resilient 30 pencil retaining loop above each support, and a pencil point protector below the same.

2. In a pencil carrier formed by a plate 35 of thin sheet metal, a resilient finger formed on one end thereof adapted to hold said pencil carrier within the pocket of a garment, a vertical tubular pencil support formed on each edge of said plate intermediate the ends, a resiliently mounted pencil retaining loop above each support formed on a folded 40 lateral projection and adapted to clamp the pencil when inserted in the support, and a point protector for the pencil below the support.

3. In a pencil carrier formed of a plate of 45 thin sheet metal, a resilient finger formed

on one end thereof adapted to hold said pencil carrier within the pocket of a garment, a vertical tubular pencil support formed on each edge of said plate intermediate its ends, a lateral projection from each edge of said plate above the support, each projection being bent upon itself and formed with a pencil retaining loop over said support, and a point protector for the pencils extending transversely of the plate below the supports 55 and integral with said plate.

4. A pencil carrier comprising a base plate made of thin sheet metal having an integral end finger at the top thereof to clamp said pencil carrier within a pocket, a tubular pencil support on each vertical edge of said plate, a resiliently mounted extension above each tubular support integrally formed from laterally extending strips of said base plate and serving to clamp pencils 60 65 when inserted in said support, and a protector for the pencil point at the lower edge and integral with said plate having openings coincident with the lower ends of the tubular supports.

5. A pencil carrier formed integrally from a plate of thin sheet metal and comprising a spring finger at the top, a tubular pencil support at each vertical edge, a resilient extension on each lateral edge of said 70 plate bent upon itself and formed with a loop, each of said loops being immediately above a pencil support and serving as a clamp for the pencil, and a pencil point protector triangular in cross section extending 75 transversely beneath said tubular supports and having openings through one side continuous with said supports to hold the pencil points in suspension.

In testimony whereof I affix my signature 85 in presence of two witnesses.

THADDEUS L. POWELL.
